UNITED STATES PATENT OFFICE.

JOHN H. SCHUSSLER, OF CHICAGO, ILLINOIS, ASSIGNOR TO ACME PRINTING APPLIANCE CO., OF CHICAGO, ILLINOIS.

INKING-ROLL TRUCK FOR PRINTING-PRESSES.

1,342,355.

Specification of Letters Patent. Patented June 1, 1920.

Application filed November 30, 1917. Serial No. 204,599.

To all whom it may concern:

Be it known that I, JOHN H. SCHUSSLER, a citizen of the United States, residing at Chicago, in the county of Cook and State 5 of Illinois, have invented a certain new and useful Improvement in Inking-Roll Trucks for Printing-Presses, of which the following is a full, clear, concise, and exact description, reference being had to the accompanying 10 drawings, forming a part of this specification.

The invention relates to inking roll trucks for printing presses and primarily to that type of these devices in which the truck 15 controls the roll and holds it away from the type during its travel in one direction, the truck being operable to bring the roll to a position in which the roll engages the type when it travels in a reverse direction.

20 The roller to which the truck is applied is a supplementary or auxiliary roller which is operated and brought into contact with the type to ink them after the operation of the other rolls.

25 The object of an invention of this character is the even distribution of the ink. Without the supplemental roll the inking of the type surface is uneven by reason of the fact that during the first rotation of the 30 ink rolls after leaving the ink disk the greater portion of the ink is deposited upon the uppermost or first type, the latter or subsequent type receiving only a comparatively small amount of the ink originally 35 deposited upon the rolls. The supplemental roll is kept raised from the face of the type after it leaves the ink disk, and is only permitted to contact with the type upon the return stroke of the arm by which these rolls 40 are carried. This insures a deposit of ink upon the lowermost type which results in an even distribution of ink upon all of the type and insures uniform impressions.

45 It is an object of the invention to produce these and other advantages in a simple and expeditious manner without resulting in a corresponding reduction in efficiency.

The invention has as a further object certain details of construction which will be 50 explained in detail in conjunction with the accompanying drawings, in which—

Figure 1 is a side elevation of a portion of a press having the invention applied thereto;

55 Fig. 2 is a front elevation of a portion of

the structure shown in Fig. 1, showing the truck positioned upon the part of the press with which it coöperates;

Fig. 3 is a central section of the truck shown in Figs. 1 and 2;

Fig. 4 is another section of the truck taken on line 4—4 of Fig. 5;

Fig. 5 is an end view of the truck; and

Fig. 6 is a central section of a modified form of the invention.

In the drawings the invention is illustrated as applied to a press of the type which employs a swinging frame 10 having the ink disk 11 and the swinging arms 12 to which the trucks are attached, which carry 70 the ink rolls 13—13, and the supplementary roller 14. This frame 10 is actuated by the crank arm 15 connected to the gear 16, as is usual in this type of press. The swinging arms 12 carry the rollers 13—13 and supplemental roller 14 from the ink disk 11 across the face of the type and back again. These rollers 13 and 14 have trucks 16^a and 17 respectively, provided at their opposite ends, which ride upon the tracks 18. The 75 upper ends of these tracks terminate near the disk or plate 11 and the lower ends being beveled as shown at 19. This beveled portion 19 coöperates with the truck 17 of the supplementary roller 14 and actuates it 80 and positions the roller 14 so that it engages the face of the type upon its movement in an upwardly direction. This position of the roller is maintained until it reaches the uppermost end of the track when the truck 85 is brought into the path of the track and rides thereon during the downward travel thereof from the ink disk 11, holding the roller away from the face of the type. The truck generally designated 17 is mounted 90 upon the end of the shaft 20 of the supplemental or auxiliary roller 14 by the member 21, which is made fast with the shaft 20 by the key 22. This key also limits the movement of the member 21 toward the roller 100 14. The member 21 has a sleeve 23 which is passed over the end of the shaft 20. This sleeve has the flanged portion 24; the width of this member 21 is somewhat greater than the width of the tracks 18. Upon the sleeve 105 23 is mounted the member 25 having the high and low treads 26 and 27, which is movable lengthwise of the sleeve, the low tread being substantially greater in width than the high tread 26 for the reason that greater traction 110

is necessary to operate the roller 14 when this portion rides against the track because when this portion is in contact with the track the type are being inked by the supplementary roller 14, which is driven by this part 5 of the truck.

This member 25 abuts against the flange 24, and is held against the same by the coiled springs 34. The portion 25 is provided with the apertures 30—30 having the reduced portion 31. Into these bores are fitted the headed pins 32 one end of which are driven into the flange 24 of the member 21. A coiled spring 34 is placed in the 15 larger portion of the bores 30—30 and reacts between the head of the pin 32 and the shoulder 35 of said bore. This arrangement tends to keep the collar having the treads 26 and 27 and the collar having the 20 flange 24 together, as shown in Fig. 3, but permits them to separate when caused to do so by the beveled portion 19 of the tracks 18. These pins 32 further cause the two members 23 and 25 and their associated 25 parts to rotate together to drive the roller 14, eliminating any relative rotation and the necessity of additional keys, etc., for this purpose.

An arrangement is provided whereby a 30 relative adjustment of the parts 23 and 25 may be had, which is of advantage in that the treads may be arranged so as to properly coöperate with tracks of various widths. Should a condition arise in which the truck 35 had to be positioned on the shaft 20 approximately in the relation shown in Fig. 3, and the track 18 was found to be somewhat wider than illustrated, under these conditions it would be of advantage to be able 40 to adjust the collar having the treads 25 and 26 so that the higher tread 26 would be in proper position to engage the beveled portion 19 for the proper operation of the device. To arrange for this contingency 45 the member 21 is provided with the adjusting screws 34 and the set screw 35, which may be operated to separate the members 21 and 25. The member 21 being fixed would naturally cause the member 25 having the treads to be shifted or adjusted with 50 relation to the track 18. These set screws may be arranged in the flange 24 instead of in the member having the treads 26 and 27.

55 In the modified form shown in Fig. 6, a single coiled spring 36 is used and the pins 32 are dispensed with. This structure contemplates the use of a collar 37 having a flange 38 and the screw threaded end portion 39. Over this collar 37 is passed the portion 40 having the treads 41 and 42, and the inwardly projecting flange 43. This flange 43 and the flange 38 form a recess 60 which houses the coiled expansion spring 65 36, which reacts against these flanges. A

nut 44 is threaded upon the portion 39 which holds the parts in the relative position shown in Fig. 6. The portion 45 of this nut 44 has flat sided portions as has the inner face of the flange 43. This insures 70 against a relative rotation of the parts and compels them to rotate with the shaft to which they are attached. To prevent the part 37 and the nut 44 from being separated or unscrewed during the operation of the 75 device, these parts are fastened together by the key 46. This construction may also be adjusted by the adjusting screws 47 similar to those shown and described in connection with the structure illustrated in Figs. 3 80 and 4.

The operation of the trucks which control the auxiliary rolls 14 is substantially as follows: As the inking rollers leave the disk 11 in their downward travel with the 85 rollers 13—13, the high part of the truck of the auxiliary roller rides over the uppermost end and upon the track 18, lifting this roller away from the type and holding it out of contact while the rollers 13—13 contact with the type and ink them. After these inking rollers 13—13 leave the printing surface of the type and are about to begin their return movement, the high part 90 of the trucks engages the beveled portion 19 of the track 18 and slips off. As soon as this occurs the low tread part of the trucks engages the top of the track, while the high part engages and travels along the side thereof, and as the rollers including the 100 auxiliary roller 14 travel upwardly, the roller 14 is brought for the first time into contact with the printing surface of the type, distributing the ink which it received from the disk 11 upon the lowermost type. This insures the proper and even inking of the type so that when an impression is 105 taken, all of the type will be equally pronounced. While the roller 14 is inking the type, the high part of the truck travels along the side of the track 18. This brings the low tread against the track, which furnishes the traction necessary to rotate it. At this time the springs are compressed by 110 virtue of the fact that both of these treads are secured by the pins to the part which is immovably fixed to the shaft of the roller 14. When the high tread reaches the uppermost end of the track it passes from the side of the track into the path thereof, this being caused by the expansion of the 115 springs, and upon its travel from the inking disk 11 the inking roller 14 will be lifted away from the face of the type and the subsequent action will be a repetition of that just described.

Having thus described the invention what I claim and desire to cover by Letters Patent is:

1. In a device of the class described, the 120

combination of a truck having a high and low tread construction to coöperate with a track to raise and lower the truck, said truck being secured to an end of a roller and having means for adjusting the truck with relation to the track, said means being movable with the truck when same is moved to present the high and low treads to the track.

2. In a device of the class described, the combination of a truck having high and low treads constructed to alternately ride upon a track, a member stationarily arranged upon the end of the roller, the truck being slidably arranged upon said member, a pin extending from said stationary member into the bore provided in a truck, said pin having an enlarged end and terminating substantially flush with the outer face of the truck when the truck is in contact with the member which is secured to the roller, the enlarged end of the pin closing the bore of the truck, and being movable into the bore when the truck is moved and a spring reacting between the enlarged end of the stationary pin and the end of the bore of the slideable member for holding the truck in contact with said member.

3. In a device of the class described the combination of a truck having high and low treads constructed to alternately ride upon a track, a member secured to the end of a roller, means for yieldably holding said truck in contact with said member, and means for separating said truck and said member to adjust and hold said truck in adjusted position with relation to the track.

4. In a device of the class described, the combination of a truck having high and low treads constructed to alternately ride upon a track, a member secured to the end of a roller, means for yieldably holding said truck in contact with said member, and means for separating said truck and said member to adjust and hold said truck in adjusted position with relation to said member and the track.

5. In a device of the class described, the combination of a truck having high and low treads constructed to alternately ride upon a track, a member secured to the end of a roller, a pin having an enlarged end projecting from said member, said truck having a bore in which said pin is arranged,

one end of said bore being closed by said enlarged end of the pin, a spring arranged in the bore and reacting between the enlarged end of the pin and one end of the bore, and means for separating said truck and said member to adjust and hold the truck in adjusted position with relation to the member and the track.

6. In a device of the class described, the combination of a member constructed to be secured to the end of a roller, another member arranged for endwise movement upon the member which is secured to the roller, said second mentioned member having means whereby said roller may be alternately raised and lowered, the first mentioned member having a flange, means extending from the flange and engaging the second mentioned member, said means having means tending to keep the second mentioned member against the flange of the member constructed to be secured to the roller, means for adjusting said truck with relation to the flanged member, and means for separating the second mentioned member from the member which is secured to the end of the roller.

7. In a device of the class described, the combination of a truck having a high and low tread construction to coöperate with a track to raise and lower the truck, said truck being secured to an end of a roller and having means for moving the truck to adjust the same, said means forming a means for holding the truck in adjusted position and being movable with the truck when the truck is moved to present the high and low treads to the track.

8. In a device of the class described, the combination of a truck having high and low treads constructed to alternately ride upon a track, a member secured to the end of a roller, means for yieldably holding the truck in contact with said member, and means for separating the truck and said member to adjust the truck with relation to said member, said means forming a means for holding said truck in adjusted position with relation to said member.

In witness whereof I hereunto subscribe my name this 10th day of November, A. D. 1917.

JOHN H. SCHUSSLER.
